(57) **CLAIM**

The ornamental design for a beacon cradle, as shown in the drawings and described above.

DESCRIPTION

FIG. 1 is a top perspective view of a beacon cradle, showing our new design.

FIG. 2 is a left elevational view of the beacon cradle of FIG. 1.

FIG. 3 is a right elevational view of the beacon cradle of FIG. 1.

FIG. 4 is a front elevational view of the beacon cradle of FIG. 1.

FIG. 5 is a rear elevational view of the beacon cradle of FIG. 1.

FIG. 6 is a top plan view of the beacon cradle of FIG. 1; and, FIG. 7 is a bottom plan view of the beacon cradle of FIG. 1. Dash-dash broken lines illustrate portions of the beacon cradle that form no part of the claimed design. Long dash-short dash broken lines depict boundaries and form no part of the claimed design.

1 Claim, 6 Drawing Sheets
